UNITED STATES PATENT OFFICE.

CHARLES B. STILWELL, OF PHILADELPHIA, PENNSYLVANIA, ASSIGNOR TO
THE UNION PAPER BAG MACHINE COMPANY, OF SAME PLACE.

PAPER-BAG MACHINE.

SPECIFICATION forming part of Letters Patent No. 508,061, dated November 7, 1893.

Application filed April 17, 1893. Serial No. 470,624. (No model.)

To all whom it may concern:

Be it known that I, CHARLES B. STILWELL, a citizen of the United States, residing in Philadelphia, in the county of Philadelphia, in the 5 State of Pennsylvania, have invented a certain new and useful Improvement in Paper-Bag Machines, of which the following is a true and exact description, reference being had to the accompanying drawings, which form a 10 part of this specification.

My invention relates to paper bag machines having the leading characteristics of the machines described in my Patents No. 407,794, of July 30, 1889, and No. 417,346, of December 15, 1889.

The object of my present invention is to substitute for the roller marked L' in the patent of July 30 a device which will not engage the paper nor offer any resistance to its forward or backward movement, except at the time when the distension of the tube is being accomplished.

The nature of my improved device will be best understood as described in connection 25 with the drawings in which it is illustrated and which drawings represent a machine substantially identical, with the exception noted, of that shown in my earlier patents.

In said drawings, Figure 1 is a perspective 30 view of the parts of the machine immediately connected with my improvement, and Fig. 2 is a vertical longitudinal section of said part of the machine.

A, indicates the frame; B, the lower feed 35 roller having upon it gripping fingers B', one of which is indicated in Fig. 1, and which in character and operation is the same as those shown in my earlier patents.

C, is the coacting feed roller resting upon 40 the roller B.

D and D' Fig. 2, are feed rolls acting to carry and deliver the blanks to the rollers B and C.

E is a roller placed in front of the rollers 45 B and C, and under which the blanks are fed as in my former machines.

F is the tucker operating between the rollers C and E, said tucker being actuated through a lever F' attached to a rock shaft F'.

50 G is a guide bar supported on the bracket G' attached to part of the frame.

H, indicates a metal plate lying to the rear of the guide bar G and extending somewhat over the feed roll I; J being the co-acting feed roll.

55

K is a rock shaft having at one end a lever K' carrying a cam roller K² which rests against the periphery of a cam L.

K³ is another lever arm connected with the rock shaft K and to which is attached a spring 60 K⁴ the action of which holds the cam roller K² in contact with its cam.

M, indicates an upright arm, of which there are two attached to the rock shaft K, and to which arms are in turn attached the fingers 65 M', M² being rods extending downward from said fingers and carrying cam rollers M³ which rest against cams N.

In all of the parts above described my present machine is in no wise different in construction or operation from the machines de-

scribed in my former patents, and it is not necessary therefore to elaborately describe the operation of said parts. Instead however, of providing a roller below the roller E and 70

pressing against it at all times so as to nip the upper ply of the blank, I provide a spring finger P, the end P' of which rests beneath the roller E and is alternately carried up 75

against said roller and down below and out 80 of contact with it; the mechanism actuating said spring finger carrying and holding it below the roller E while the blank is being fed beneath said roller, and then carrying it up

to nip the blank against the roller E just before and during the time when the fingers M' are performing their function upon the blank; that is to say, engaging the upper corners of the upper ply of the blank Q and co-acting 85

with the fingers B', which engage the corresponding corners of the lower ply, in distending the blank to the box like form shown in 90

Fig. 1 and described in my former patents; immediately after the fingers M' have performed their work upon the blank the spring 95 finger is moved downward, releasing the upper ply of the blank so that it is drawn backward from beneath the roller E without encountering resistance. In the plan shown, the necessary movements are given to the 100

finger P by attaching it to an upright standard O attached in turn to the rock shaft K;

- by this attachment it is obvious that the finger P is thrown up at the same time with the fingers M' which are also attached to the same rock shaft through their parts M. Obviously 5 also the motion of the rock shaft K which throws the fingers M' down also moves the spring finger P, thus disengaging the blank from the nip of the spring finger and the roller E.
- 10 Having now described my invention, what I claim as new, and desire to secure by Letters Patent, is—
1. In a bag machine substantially as described, the combination with the roller B and 15 the grippers B' acting to engage the lower ply of the blank, of the fingers M' M' acting to

engage the upper ply and coact with the fingers B' in distending the blank, the roller E, a spring finger P and means acting on said finger to move it to and from the roller E. 20

2. In a bag machine substantially as described the combination with the roller B and the grippers B' acting to engage the lower ply of the blank, a rock shaft K, fingers M' M' connected with said shaft, a roller E lying 25 above the points of said fingers and a spring finger P also connected with and actuated by the rock shaft.

CHAS. B. STILWELL.
